(57) **CLAIM**

The ornamental design for cap, as shown and described.

DESCRIPTION

FIG. 1 is a perspective view of a first embodiment of a cap showing my new design;

FIG. 2 is a front view of FIG. 1

FIG. 3 is a perspective view of a second embodiment of a cap showing my new design

FIG. 4 is a front view of FIG. 3

FIG. 5 is a perspective view of a third embodiment of a cap showing my new design

FIG. 6 is a right side view of FIG. 5

FIG. 7 is a perspective view of a fourth embodiment of a cap showing my new design; and,

FIG. 8 is a left side view of FIG. 7.

The broken line showing of the visor is for illustrative purposes only and forms no part of the claimed design, and the broken lines shown on the crown represent stitching.
